Inventor.

United States Patent Office.

HENRY A. LEE, OF WORCESTER, MASSACHUSETTS.

Letters Patent No. 79,663, dated July 7, 1868.

IMPROVEMENT IN MOULDING-MACHINES.

The Schedule referred to in these Letters Patent and making part of the same.

KNOW ALL MEN BY THESE PRESENTS:

That I, HENRY A. LEE, of the city and county of Worcester, and Commonwealth of Massachusetts, have invented certain new and useful Improvements in Moulding and Planing-Machines; and I do hereby declare that the following is a full, clear, and exact description of the same, reference being had to the accompanying drawings, forming a part of this specification, and in which—

Figure 1 represents a perspective view of so much of a Lee moulding and planing-machine as is necessary to illustrate my present improvements.

Figure 2 represents a side view.

Figure 3 represents a top or plan view.

Figure 4 represents a longitudinal vertical central section on line A B, fig. 3; and—

Figure 5 represents a section of a part of the feed-device, on line C D, fig. 3.

To enable those skilled in the art to which my invention belongs to make and use the same, I will proceed to describe it more in detail.

In the drawings, the part lettered A is the main frame, upon one end of which are mounted the feed-rolls B B and B' B'.

The rolls B B are supported in bearings, *a*, fitted in slots or recesses cut or formed in the side-pieces of the main frame, one of which is seen in fig. 1.

The boxes or bearings rest upon the heads of screws or bolts, and are held down by screws *b*, which pass through the caps *c*. By this arrangement the rolls B B can be adjusted up or down.

The journals of the upper feed-rolls B' B' are supported in the boxes *d d*, which are fitted to work in the slots or grooves *e e*, concentric with shaft C', in the wings C C of the sliding pieces D, the lower ends, D', of which have slots, *f*, through which the holding-rod 1 passes. The lower ends, D', are fitted in slots or recesses, *g*, in the sides of the main frame, whereby the sliding pieces, D, which support the bearings of the upper feed-rolls, are retained securely in their proper positions.

A central shaft, C', passes through the sliding pieces D, and is provided, on each end, with a spur-gear, 2, to mesh into the gears 3 3 3 on the journals of the feed-rolls B' B'.

The shaft C' has, on one end, a spur-gear, 4, which meshes into the spur-gear 5, the journal of which is supported in the ends, 6 7, of the links 8 and 9. Gear 5 meshes into gear 10 on the outer feed-roll B.

The bottom feed-rolls B B are, at the opposite side of the machine, provided with gears 11 11, which both mesh into the middle gear 12, which turns upon a stud or journal, fast in the side of the main frame.

The feed-rolls B' B' are held down by the rods 13 13, which are hooked upon their journals at each end, the rods 13 being drawn down by the weighted levers 14 14, hinged to the lower end, D', of the slide-piece D, as fully indicated in fig. 4.

The lower ends, D', are formed with inward projections, 15, to receive the elevating and depressing-screws 16, supported in bearings 17, and having gears, 18, to fit the gears 19 on the shaft 20, which runs across the machine, and by the turning of which the screws 16, one being attached to each side of the machine, can be revolved to elevate or depress the slide-pieces D and the top rolls B' B', whenever desired.

It will be seen, from the foregoing description, that the feed-rolls B' B' can both rise and fall independent of each other, while at the same time their gears 3 3, at each end, remain in gear with the gears 2 2 of the stationary central shaft C', the mesh of the gears being the same at all times, owing to the fact that the boxes or bearings *d d*, of the rolls B' B', move in circles concentric with shaft C'.

Motion is imparted to gear 4, fast on the end of shaft C', from the gear 10, on one of the lower feed-rolls, through the intervention of the gear 5, supported in the ends 6 and 7 of the links 8 and 9, which are fitted to turn on the journals of the shafts of the gears 10 and 4, as indicated in the drawings.

It will thus be seen the elevating or depressing of the shaft C' does not affect injuriously the mesh of the gears 4, 5, and 10.

The feed-device above described is strong, and at the same time easy of adjustment in every respect, thus avoiding much friction and many of the objections incident to other modes of constructing the feeding-mechanism of moulding and planing-machines.

After the slides D have been elevated or depressed to any desired position, they are fastened and held securely in place by the holding-rod 1, in the following manner:

A nut, v, is fitted into a groove or slot, x, in one of the sliding pieces, D, and through which the holding-rod 1 is screwed, while upon the other end of the same screw or holding-rod 1 are two nuts, w w, one of which answers as a check-nut. The point of the rod 1 passes beyond the nuts w w, and enters the side of the frame A, as fully shown in Figure 6, which is a central section of the rod and the parts near it. When in this position, the slides D D are clamped securely without occasioning any spreading of the sides of the frame A. To loosen the sliding pieces D D, holding-rod 1 is unscrewed, which withdraws the shoulder t, of the wheel A', from the side of frame A, and nuts w w from the side of the projecting part D' of the piece D.

The cylinder or cutter-head E is supported in bearing E' E', which are fitted to slide up and down on the faces of the stands F F. Combined with the bearings E' E' are two adjusting-screw shafts, G, supported at their lower ends by boxes m, fastened to the inner sides of the main frame, and having shoulders 23, which rest on the flanges of the stands F F, as fully shown in figs. 1, 2, and 4.

Upon the lower ends of the shafts G are gears 21, to mesh into gears 22, one on each end of shaft 24. By this arrangement the cutter-cylinder E can be set up and down with great convenience, and when once adjusted can be securely fastened by the screw-bolts n n, which pass through slots in the stands F F, while the gearing, by which the adjustment is effected, is all below the top of the frame, and thus out of the way of the workmen, and less liable to become clogged by flying chips and dirt.

H is a guide or presser-bar, supported by the bolts o o, passing through slots in the stands I, through the upper ends of which pass the adjusting-screws p p, as indicated in the drawings, whereby said presser or guide-bar can be adjusted up and down in a horizontal position, or one end can be elevated or depressed independently of the other end.

The bottoms of the stands are slotted, so that they can be moved forward or back to adjust the bar H nearer to or farther from the cutters on the cylinder E.

The cutter-heads J J are fastened to the upright shafts K K, near their upper ends, while the driving-pulleys K' K' are fastened to their lower ends, which are stepped in the projections L L on the bottoms of the upright bars M M, the lower ends of which are notched out to fit the cross-bars 30 30, and upon which they rest and slide.

The upper ends of the bars M M are supported upon the cross-bars or rods 31 31, which pass from side to side of the main frame.

The upright shafts K K pass through the projections L' L', upon the upper ends of the bars M M, so that the shafts K have a secure support, just under or below the cutter-heads J J, while the upper ends of said shafts extend above the cutter-heads, and are supported by the bearings N N, secured to the slotted cross-bar N' by screw-bolts 32 32, which pass through the slot or opening 33 in bar N'.

The bearings N N have lips, 34 34, which lap over the top of the bar N', which has legs or stands, O O, by which it is fastened to the sides of the main frame, so as to occupy an intermediate position between the shafts K K, whereby it answers for the support of both of the upper bearings of the shafts K K, one bearing being fastened on each side of the bar.

The shafts K K can be adjusted to or from each other by simply loosening the screws 32, and sliding the bars M M upon their respective cross-rods 31 31, and cross-bars 30 30.

If preferred, the cross-rods 31 31 may be provided with screw-threads to fit and work in threads in the bars M M, and hand-wheels, whereby they can be turned by hand to adjust the shafts K, or either of them, independently of the other, to cut mouldings upon pieces of wood of different sizes or widths.

It will be seen that the upright shafts, upon which the cutter-heads J J are placed, are firmly supported both above and below the cutter-heads.

Those skilled in the art of cutting mouldings will at once appreciate this part of my invention, since it obviates one great difficulty heretofore met with in the practical operation of moulding-machines in which the shafts do not have a top support.

In this last-named class of machines, the cutter-head, when driven rapidly, vibrates so much as to make "chattered" or uneven work, an objection which is entirely obviated by my mode of supporting the shafts both above and below the cutter-heads, as above described.

In the drawings, a piece of material, P, is represented as being fed through between the feed-rolls B B' B', and it will be noticed that the upper feed-rolls, B' B', have been elevated, but the gears of said rolls remain in mesh on the true pitch-line, and thus work as free and easy in one position as another.

The bolts o o pass through slots in the stands I I, and through holes in the end of the presser-bar. The heads o' o' of the bolts are flattened, and screw-holes made to receive the ends of the adjusting-rods p p. When the nuts on the ends of the bolts o o are screwed on, the shoulders of the flattened heads o' o' are drawn against the ends of the presser-bar, thereby binding it firm against the stands I I. As the parts of the bolts o o which pass through the ends of the presser-bar are round, the presser-bar turns freely on said bolts, when either end is raised above or depressed below the other end.

Having described my improved moulding and planing-machine, what I claim therein as new, and of my invention, and desire to secure by Letters Patent, is—

1. The combination, with the lower feed-rolls B, the upper feed-rolls B', the adjustable pieces D, and their

concentric slotted arms C, and the central shaft C', of gears 2, 3, 4, 5, 10, 11, and 12, and links 8 9; constructed and arranged for joint operation, as and for the purposes set forth.

2. The combination, with the stands F and the sliding bearings E, held to said stands by bolts n, of the elevating and depressing-shafts G, with their shoulders 23, the parts being constructed and arranged with relation to each other as and for the purposes set forth.

3. The combination, with the presser-bar H, arms I, and screw-rods p, of the peculiarly-constructed holding and swivel-bolts o, the parts being constructed and arranged with relation to each other as and for the purposes set forth.

4. The combination, with the upper end of each or either of the shafts K, and the slotted bar N', of the peculiarly-constructed bearing-piece N, in the manner and for the purposes shown and set forth.
